UNITED STATES PATENT OFFICE.

KATHERINE WALL, OF OMAHA, NEBRASKA.

MARCELLING AND PERMANENT-WAVE IRONS.

Application filed September 13, 1927. Serial No. 219,327.

The invention relates to marcelling and permanent wave irons, and has for its object to provide a device of this character wherein a plurality of irons have electric 5 cord connections with an overhead socket carrying device and spring rollers carried by said socket device, and over which flexible members extend, which flexible members terminate in clamps adapted to receive and support the marcelling iron at the proper elevation during a marcelling operation. The rollers are preferably of a conventional spring type which support articles at predetermined heights.

10 A further object is to provide a marcelling iron comprising a handle member having a forked device, the arms of which are in parallel relation and a plate pivoted to the handle member and provided with transverse corrugations in which are received the arms of the forked member whereby the hair will be waved when clamped between the plate and the arms of the forked member. Also to provide spring means for normally 15 forcing the plate towards the arms of the forked member and exerting pressure on the clamped hair during the marcelling operation.

20 A further object is to provide a curved under plate having pins adjacent its ends and which pins, when the curved under plate is in position, are received within the corrugations of the upper side of the corrugated plate and forms a protective shield for the head, as well as means for holding the hair against the arms of the forked member. Also to provide the under plate with a heat insulating layer for additionally protecting the head.

25 A further object is to provide the under side of the pivoted corrugated plate with transverse ridges for preventing lateral displacement of hair between the plate and the arms of the forked member.

30 With the above and other objects in view the invention resides in the combination and arrangement of parts as hereinafter set forth, shown in the drawing, described and claimed, it being understood that changes in 35 the precise embodiment of the invention may be made within the scope of what is claimed without departing from the spirit of the invention.

40 In the drawings:

45 Figure 1 is a side elevation of the waving iron and supporting device therefor.

Figure 2 is a bottom plan view of the socket carrying device.

Figure 3 is a perspective view of one form of the iron wherein a single convolution is 60 used.

Figure 4 is a perspective view of the iron showing a plurality of corrugations.

Figure 5 is a perspective view of the protecting plate.

Figure 6 is a perspective view of a hair clamping device for holding the hair while placing the marcelling device thereon.

Referring to the drawings, the numeral 1 designates the ceiling of a room and 2 a casing secured thereto in any suitable manner, which casing is provided with a plurality of electric sockets 3, preferably circumferentially arranged as shown in Figure 2. Disposed within the casing 2 are conventional 70 forms of spring rollers 4, for instance of the shade roller type wherein the roller may be held against rotation, and extending around said rollers 4 are cords 5, which cords extend downwardly and have connected thereto at 6 V-shaped clamping members 7, which clamping members are adapted to support the marcelling irons hereinafter set forth. Cords 5 extend through the apertures 8 in the under side of the casing 2, therefore it 80 will be seen that the rollers 4 are concealed from view at all times.

Referring to Figures 3 and 4, it will be noted that in Figure 3 an iron is shown having a single corrugation, and in Figure 4 90 an iron having a plurality of corrugations, however the structures and operation are the same and the same numerals will apply thereto, and in which figures, the numeral 9 designates the handle member, adapted to 95 be grasped by the operator for manipulating the device, and leading into said handle member is an electric cord 10, the end of which terminates in a plug 11, which screws into the multiple plug socket 12, which in 100 turn screws into the socket 13 of the casing 1. By providing the multiple plug 12, it is obvious an electric lamp 14 may be received within the plug socket 12, so that the operator will know at all times whether current 105 is flowing through the electric cord 10 to the heating element, which may be disposed within the handle 9, or in the fork 15, a single arm 15^a being shown in Figure 3, and which heating element is adapted to supply 110 the necessary heat for the marcelling operation. The fork 15 has a plurality of arms

16 in spaced parallel relation and which arms preferably curve as shown in the drawings. Pivots connected at 17 to the fork 15 and the arm 15^a is a corrugated plate 5 18, which plate has its corrugations longitudinally disposed and the plate longitudinally curved to conform to the curvature of the arms 16, whereby when said corrugated plate 18 is forced downwardly by the leaf 10 spring 19, which forces upwardly the finger engaging arm 20, the hair 21 will be clamped between the plate 18 and the heated arms 16, which arms are disposed within the convolutions of the under side of the 15 plate 18, therefore it will be seen that the hair will be held during the marcelling operation. At the initial starting of the operation a split clamp 22 is preferably used for holding the hair 21 in proper spread position, and at which time the loop 23 of the 20 clamp is over the end 24 thereof. After the clamp is placed in position, the marcelling iron is adjusted to the hair.

After the marcelling device has been 25 placed on the hair, the spring clamp 7 is passed under the loops 25 carried by the upper side of the plate 18 adjacent its opposite end, consequently the clamp and the flexible member 5 will support the weight of the 30 marcelling device, and relieve the same from the head. The clamp 7 is placed in position by spreading the same until the arms 26 will be received in the outer ends of the loops 25. The under sides of the corrugated 35 plates 18 are preferably provided with grooves 27 running transversely, and which grooves form means for preventing lateral displacement of the hair when clamped in the device, and also forms means for partially spreading the hair during the clamping 40 operation.

A shield 28 is provided which shield curves substantially at the same arc as the plate 18 and arms 16, and is provided with 45 turned up edges 29, which engage over the opposite sides of the corrugated plate 18, and has its outer face preferably provided with a layer of heat insulating material 30 for protecting the head and the hair adjacent the device. The opposite ends of the 50 plate 28 are provided with apertured lugs 31, through which lugs pins 32 extend. The pins 32, after the plate has been placed in position, are forced inwardly, and are received between the corrugations of the plate 18, thereby attaching said plate 28 to the device, and in a manner whereby it may be easily and quickly removed.

From the above it will be seen that a

marcelling iron is provided which is simple 60 in construction, positive in its operation, and one which may be cheaply manufactured and sold.

The invention having been set forth what is claimed as new and useful is:—

1. A marcelling iron comprising a handle member, a fork carried by said handle member and having a plurality of arms, means for heating said fork, a corrugated plate pivotedly mounted on the fork and positioned whereby the plurality of arms will be received between the corrugations thereof, a protecting plate for the under side of said iron, said protecting plate being provided with means whereby when it is positioned said plate will be held against displacement by members overlying the corrugated plate.

2. A marcelling iron comprising a handle member, a heating fork carried by said handle member, a corrugated plate pivoted to the fork adjacent the handle member, said corrugated plate having its corrugations positioned whereby the arms of the fork will be received therebetween, U-shaped brackets carried by the upper side of the corrugated plate adjacent its ends, a protecting plate beneath the fork, the opposite sides of the protecting plate overlying the opposite sides of the corrugated plate, lugs carried by the 85 opposite ends of the protecting plate, and pins extending through said lugs and engaging between the corrugations of the corrugated plate at opposite ends thereof and forming means for holding said protecting 90 plate in position.

3. The combination with a marcelling iron, of a support therefor, said support comprising a casing adapted to be secured to a ceiling, a spring roller within said casing, a flexible member extending around said roller and forming means whereby a spring arm clamp may be supported at different elevations, said spring arm clamp being detachably connected to the marcelling arm.

4. The combination with a marcelling iron, of a support therefor, said support comprising a suspended spring roller, a flexible member extending around said roller, spaced loops carried by the marcelling iron and a flexible clamping member carried by the flexible member and detachably engaging in the eyes.

In testimony whereof I hereunto affix my 115 signature.

KATHERINE WALL.
